UNITED STATES PATENT OFFICE.

JOHN A. WHERRY, OF NEW ORLEANS, LOUISIANA, ASSIGNOR TO UNDERWOOD TYPE-WRITER COMPANY, OF NEW YORK, N. Y., A CORPORATION OF DELAWARE.

TYPEWRITING MACHINE.

Application filed May 2, 1922. Serial No. 557,873.

To all whom it may concern:

Be it known that I, JOHN A. WHERRY, a citizen of the United States, residing in New Orleans, in the parish of Orleans and State 5 of Louisiana, have invented certain new and useful Improvements in Typewriting Machines, of which the following is a specification.

This invention relates to a method of 10 typing a succession of bill and ledger sheets, and to a typewriting machine for carrying out such method.

Objects of the invention are to enable a 15 succession of sheets to be typed rapidly, one after the other, and at the same time to produce multiple copies.

A feature of novelty resides in inserting 20 a first sheet from the rear, around beneath the platen, and up past the printing line, and subsequently inserting the sheets successively, one after the other, downwardly at 25 the front between the platen and the top margin of the preceding sheet in slightly underlapping relation therewith, the platen being rotated so as to bring the successive 30 sheets down to the printing line, and to deliver the typed sheets at the rear of the platen, so that, as the platen is rotated, each 35 newly-inserted sheet is guided, by the next preceding sheet, to pass downwardly and rearwardly between the platen and the usual paper-guiding devices associated with the platen. The sheets may thus be accumulated 40 at the rear of the platen without attention from the operator, in the same order in which they are typed.

The bill and statement sheets may be arranged to form a novel entry-sheet. This 45 may comprise a bill-part having joined thereto a ledger or record-part and a stub-part to be folded into superimposed relation therewith, so that, by means of interleaved carbon-sheets, all of said sheet-parts may be typed at the same time and afterwards separated. More particularly, the 50 bottoms of the bill-part and record-part may be connected together along a transverse weakened line of detachment, along which the folding into superimposed relation may take place, and the stub-part may be connected with one of the sides of the bill-part along a vertical weakened line of

detachment, upon which the folding into superimposed relation may take place; and each of said sheet-parts may have thereon 55 a form comprising suitable item-designations to be brought into alignment when the sheet is folded for typing, so that items typed will appear under the proper item-designations on each of the parts of the 60 sheet. The novel entry-sheet forms the subject of my divisional application, Serial No. 644,235, filed June 8, 1923. The provision of a sheet of this character is important, however, in carrying out the method of 65 this application, since the forms are self-registering, the carbons are retained in correct relation to the work-sheets during downward insertion at the front of the machine, and there is but one leading edge to 70 contend with, the folded lower edge, during the insertion of the work.

The novel typewriting machine forming a feature of the present invention is a revoluble-platen front-feed machine of the 75 front-strike type, that is, a machine in which the front of the platen is the introductory side and the rear of the platen is the delivery side. The machine includes a front sheet-introducer, comprising a rotary 80 platen, a front chute including side gages for guiding a sheet to be introduced down to the front of the platen into underlapped relation to a sheet in the machine, and a paper-deflector between the side gages and 85 spaced a short distance in front of the platen to hold the sheet in the machine back against the platen at the writing line while permitting said sheet to form a wide-mouthed funnel with the floor of the chute and with the platen for the reception of the downwardly-introduced sheet. The sheet-deflector, besides holding the sheet in the machine back against the platen at the line of writing, 90 causes said sheet to extend in close proximity to the platen for a considerable distance, but does not hold it fast against the platen, so that a very acute bight is formed within which the sheet to be introduced can be gripped evenly at any position within a 95 considerable range. This gives the operator latitude in the positioning of the new sheet relatively to the one in the machine. A receptacle for the accumulation of the typed 100

work-sheets is provided at the rear of the platen, in which the sheets may be accumulated without attention from the operator.

Other features and advantages will hereinafter appear.

In the accompanying drawings,

Figure 1 is a diagrammatic end view of a platen-frame and some of the associated parts of the typewriting machine, and shows 10 how the first and second sheets are inserted in carrying out the method, the first sheet being shown at the typing position.

Figure 2 is a similar view, showing a third sheet inserted from the front and being 15 guided past the edge of the usual paper-apron by the preceding sheet as the platen is rotated, to bring the last-inserted sheet down to the typing position.

Figure 3 is a similar view, showing how 20 the successively-typed sheets are delivered at the rear of the platen, and with the last sheet inserted being brought to the typing position.

Figure 4 is a partly diagrammatic front 25 elevation, on a reduced scale, of the platen-frame, platen and paper-guiding devices, an entry-sheet being shown in broken lines.

Figure 5 is a plan view of one of the 30 entry-sheets in flat condition, and shows the side thereof which bears the forms for the record-part or ledger-sheet and for the stub-part of the bill.

Figure 6 is a perspective view, showing 35 one way of folding the entry-sheet, to bring its three parts into superimposed relation, and shows the ledger-sheet or record-part at the front, the bill-part at the back and the stub-part interposed between the bill-part and record-part.

Figure 7 is a similar view, on a reduced 40 scale, showing the bill-part at the front and the record-part or ledger-sheet at the back, with the stub-part interposed between the bill-part and record-part.

In carrying out the method of the present 45 invention, the first sheet A is inserted at the rear of the revoluble platen 1 over a shelf or rear paper-table 2, and is guided around beneath the platen above the usual releasable feed-rolls 3 by means of the usual paper-apron 4, and is advanced to the front of the platen past the printing point thereon, indicated in Figure 1 by the raised type-head 5, where it may be held in position by the usual wing-scales 6 (Figure 4), and by a front arm or finger 7 carrying a small roller 8 (Figure 1), being thus brought to the typing position, as shown in Figure 1. In inserting this first sheet A from the 50 rear, the feed-rolls 3 may be released and the sheet pushed around beneath the platen, or, in order to avoid releasing the feed-rolls, the sheet may be fed around to the typing position by rotating the platen in the required direction by means of the usual 55

finger-wheels 9 on the ends of the platen-axle 10, which is journaled in the end walls 11 of the platen-frame.

The sheet A may be adjusted by means of lateral guides or side-edge gages 12 having floor-portions 13, the lower edges of which are normally in proximity to the front 70 of the platen above the printing line, as shown in Figure 1, but which may be swung away from the platen by rotation about a transverse rod 14 along which the lateral guides or side-edge gages 12 are slidably adjustable, to accommodate sheets of different widths. The gage-supporting rod 14 is 75 fixed at its ends in brackets 15, which are secured upon the end walls 11 of the platen-frame. The outstanding lateral guides 12 enable all of the successively-inserted sheets 80 to be inserted and maintained in lateral alignment.

When the first sheet A has been typed, then a second entry-sheet B is inserted downwardly at the front of the platen between the lateral guides 12 over the floor-portions 13 thereof and between the platen and the top margin of the first sheet A, in slightly underlapping relation with the sheet A, as 85 shown in Figure 1. The sheet B is pushed down just far enough to cause its lower margin to be caught between the platen and the back of the sheet A, which will be held against the sheet B by the usual paper-guiding devices, including the apron 4 and the wing-scales 6. The front roller 8, which 90 is located in proximity to and above the printing point, is free from or clear of the platen, so as to hold the outer work-sheet A in printing position relatively to the platen while permitting the sheet to diverge 95 upwardly and forwardly relatively to the floor-portion 13, thereby making a flaring throat with the front of the platen and permitting the downward introduction of the succeeding sheet B past the roller 8, between 100 the sheet A and the platen, as shown in Figure 1. The roller 8 may be termed a sheet-deflector. When the lower edge of the newly-inserted sheet B is in position to be gripped by the platen, the platen may 105 be rotated in the direction indicated by the arrows in Figures 2 and 3, by means of the finger-wheels 9, for bringing this second sheet B down to the writing position, while the first sheet A is fed around the platen to the rear, by means of the feed-rolls 3, 110 under the platen. As the platen is thus rotated, the lower edge of the front-inserted sheet B will be guided by the overlapping first-inserted sheet A down past the paper-guiding devices comprising the wing-scales 6 and front edge of the paper-apron 4. After the typing of the front-inserted second sheet B, a third sheet C is similarly 115 inserted downwardly at the front of the platen at the back of the upper margin of 120

the sheet B, and again the platen is rotated, as indicated by the arrow in Figure 2, for bringing this third sheet C to the typing position, this latter operation being illustrated in Figure 2, in which the second sheet B is shown as guiding the lower edge of the third sheet C past the upper or front edge of the paper-apron 4, while the third sheet C is being brought down to the typing position, and at the same time the first typed sheet A is being delivered at the rear of the platen upon the inclined rear paper-table or receptacle 2.

The entry-sheets are thus successively inserted, one after the other, at the front of the platen and brought down to the typing position, and, after being typed, are delivered at the rear of the platen, each upon the next preceding typed sheet, on the receptacle 2, as shown in Figure 3, which shows the sheets A, B, C and D as having been typed and delivered upon the receptacle, while a typed sheet E is being delivered and a last-inserted sheet F is being brought to the typing position as the platen rotates in the direction indicated by the arrow. The adjustable side-edge gages 12, together with their floor-portions 13, form an introductory chute at the front of the platen for the downwardly-inserted sheets, as shown in Figures 1 and 4. The rear feed-rolls 3 form an abutment or stop at the rear of the platen to hold the accumulated typed sheets clear of the platen, as shown in Figure 3. The typed entry-sheets A, B, C, D, etc., are permitted to accumulate, one upon another, in a stack upon the rear paper-table 2, as shown in Figure 3, until the stack has reached convenient proportions for handling, for example, fifty sheets, whereupon all of the typed sheets may be removed together.

In the novel typewriting machine for carrying out the novel method, no sheet-directing means at the front of the platen are required other than the adjustable chute-forming side gages 12, so that the front and top of the platen are otherwise clear of any device which might interfere with the downward insertion of the work-sheets or with the free manipulation and adjustment of the side gages. Also, as hereinbefore noted, the front of the platen above the printing line is clear of paper-feeding devices, and the small sheet-holding roller 8 is spaced from the platen, thereby providing for the unobstructed introduction of a work-sheet downwardly in overlapping relation to the previous work-sheet, as shown in Figure 1. Furthermore, and as shown in the drawings, this novel typewriting machine requires no line-spacing mechanism other than the finger-wheels 9, by means of which successively-inserted work-sheets may be quickly lowered to the

typing position and the typed sheets delivered rearwardly of the platen upon the receptacle 2 there provided.

One of the entry-sheets, such as A, B, C, etc., appearing in Figures 1 to 4, inclusive, is shown in detail in Figures 5 to 7, inclusive. The entry-sheet comprises a bill-part 16, which may be a statement or invoice, a record-part 17, which may be a ledger-sheet, as indicated in the drawings, and a stub-part 18 for the bill-part 16. The lower or bottom edges of the bill-part 16 and of the record-part 17 are joined and are detachably connected along a transverse weakened line of detachment 19, indicated in the drawings as a line of perforations. In the form of the invention shown in the drawings, the bill-part 16 and record-part 17 are of the same width, and are also of the same length. The stub-part 18 is shown at the right side of the bill-part 16, and is detachably connected therewith along a vertical weakened line of detachment 20, indicated in the drawings as a line of perforations. The lateral stub 18 is of the same length but of less width than the bill 16. Upon each of the sheet-parts, at the top thereof, there is an identifying designation, such designations being shown in the drawings as "Bill", "Ledger sheet", "Stub". Each of the sheet-parts also bears on its front or face a form which may comprise suitable item-designations arranged transversely in columns, each column being provided with the proper heading. In the particular entry-sheet shown in Figures 5 and 6 of the drawings, the bill-part 16 is shown as provided with seven item-designations for corresponding item-receiving columns, while the record-part or ledger-sheet 17 is provided with the same item-receiving columns and item-designations similarly arranged from left to right; and the ledger-sheet 17 is also further provided, at the right side, with four additional column-designations and columns to receive additional data, which is to appear upon the ledger-sheet but not upon the bill, nor upon the stub, and which in some cases may be filled in upon the ledger-sheet at a later date. The lateral stub-part 18 is shown as provided with only three item-receiving columns and column-designations, which correspond to the last three columns and column-designations on the bill-part 16, and which also correspond to the fifth, sixth and seventh columns and column-designations on the ledger-sheet or record-part 17, as it is desired that the stub-part shall contain information corresponding only to a part of the information which is typed upon the bill-part 16 and record-part 17. It is to be noted that the item-designations on the bill-part 16 are upon one side of the entry-sheet, while the item-designations 130

for the record-part 17 and for the stub-part 18 are upon the other side of the entry-sheet. It is to be further noted that the item-receiving columns and column-designations on the bill-part 16 are in vertical alignment with the corresponding columns and column-designations on the record-part or ledger-sheet 17, and that the column-designations on each of these sheet-parts are arranged at the same distance from the tops or upper edges thereof, so that, when the bill-part 16 and the record-part 17 are folded over towards each other along the transverse perforated line 19, as indicated in Figure 6 or 7, the columns and item-designations on the bill-part 16 will be brought into correct register with the corresponding columns and item-designations on the record-part or ledger-sheet 17. It is also to be noted that the columns and column-designations on the stub-part 18 are in transverse alignment with the columns and column-designations on the bill-part 16, and that the columns and item-designations on the stub-part 18 terminate at the same distance from the vertical line of perforations 20 as do the columns and column-designations on the bill-part 16, so that, when the stub-part 18 is folded along the perforated line 20, the columns and item-designations on the stub-part will be brought into register with the corresponding columns and item-designations on the bill-part 16, as indicated in Figures 6 and 7; and also at the same time, obviously, will be brought into register with the corresponding columns and column-designations on the record-part or ledger-sheet 17 in the folded condition of the entry-sheet. It follows, therefore, that, when the entry-sheet is folded from the flat condition thereof shown in Figure 5, along the perforated lines 19 and 20, the three-sheet-parts will be superimposed with the corresponding columns and item-designations of all the sheet-parts in proper register, as will be clear from Figures 6 and 7, in which, however, the folded superimposed sheet-parts are shown as slightly separated for clarity of illustration.

Figures 6 and 7 illustrate, respectively, two different ways in which the flat entry-sheet shown in Figure 5 may be folded for bringing its three parts into superimposed relation for typing all these parts at the same time. In Figure 6 the stub-part 18 is shown as folded over upon the front of the bill-part 16, and the bill-part 16 and ledger-sheet 17 are folded together with the ledger-sheet 17 at the front while the bill-part 16 is at the back of the ledger-sheet 17, with the stub-part 18 interposed between the bill-part 16 and ledger-sheet 17. According to the manner of folding the entry-sheet shown in Figure 7, the stub-part 18 is folded over upon the back of the bill-part 16, while the bill-part 16 and ledger-sheet 17 are folded

together with the bill-part 16 at the front and the ledger-sheet 17 at the back, with the stub-part 18 interposed between the bill-part 16 and the ledger-sheet 17. It is to be understood, of course, that carbon-sheets will be interleaved between the respective sheet-parts, so as to reproduce the items desired. In the manner of folding the entry-sheet shown in Figure 6, the ledger-sheet 17 will be an original or ribbon-copy while the bill 16 and its stub 18 will be carbon-copies. According to the manner of folding the entry-sheet shown in Figure 7, the bill 16 will be the original or ribbon-copy while the ledger-sheet 17 and bill-stub 18 will be carbon-copies. Obviously, if desired, the stub 18 could be folded over behind both the ledger-sheet 17 and the bill 16.

After the typing operation, the ledger-sheet 17 is detached and kept in the office while the bill 16 together with its attached stub 18 is sent to the customer, who detaches the stub 18 from the bill 16, keeping the bill and returning the stub with his check, as is customary. The record-part or ledger-sheet 17 is shown as provided in its upper margin with holes 21 for use in filing the ledger-sheet.

In Figure 7 eight item-receiving columns are shown on the bill 16 and its stub 18, instead of the seven columns shown in Figures 5 and 6, thereby, in Figure 7, providing for an additional item which may also appear in a corresponding additional column on the ledger-sheet 17.

In making out in succession numerous small bills, such as electric-light-bills, of which samples are shown in the drawings, gas-bills, and the like, which usually contain only one or possibly two lines of writing, and of which it is desired to have an office record and also a returnable stub, it has been found that much time can be saved by the hereinbefore-described rapid method of typing and by the use of the three-part sheet shown in the drawings, and also by the use of the novel typewriting machine shown in the drawings and hereinbefore described.

Variations may be resorted to within the scope of the invention, and portions of the improvements may be used without others.

Having thus described my invention, I claim:

1. In a front-feed, front-strike typewriting machine, the combination with writing instrumentalities, of a front introducer for work-sheets comprising (1) a revoluble cylindrical platen, (2) a sheet-deflector in proximity to but spaced from the platen above the writing line thereof to hold back in writing position a work-sheet in the machine, and to cause said sheet to form with the platen a very acute bight for gripping uniformly and drawing down to writing position an underlapped succeeding sheet

inserted downward in said bight, and (3) a guiding and supporting chute for the succeeding sheet comprising side gages, located at opposite sides of the deflector, and having 5 floor portions extending downward in convergent relation to the work-sheet held back by the deflector, to form a funnel therewith, said side gages being completely separated to give clearance for the passage of the operator's fingers between them clear down to the platen, so that the operator may conveniently draw forward the upper edge of the sheet in the machine to increase the 10 width of the mouth of the funnel formed by said sheet and the floor portions of the side gages, or may press said sheet in the machine back against the platen to increase the grip of the platen and said sheet upon the underlapped sheet which is being introduced into the machine.

2. In a front-feed typewriting machine of the front-strike type, the combination with a revoluble platen, of a work-introducing chute standing approximately in 25 vertical position above the front of the platen and extending down substantially to the printing line thereon, and comprising a pair of side gages each having a floor portion, said gages being separated to give clearance 30 for the introduction of the operator's fingers between the work-sheet and the platen, the platen being clear of paper-feeding devices above the printing line, so as to permit the ready introduction of a work-sheet 35 downwardly in underlapping relation to the previous work-sheet, means immediately below the printing line to hold the work-sheets against the platen, said holding means tending to cause a stiff work-sheet to

project upwardly and forwardly therefrom 40 in a position tangential to the platen, a sheet-deflector between the side gages to engage the upper portion of the work-sheet between its ends, to bend it back sufficiently to hold it against the platen at the printing 45 line and cause the sheet to form with the platen an acute bight for the entry of an underlapped sheet inserted downwardly in said bight, a feed-roll running upon the bottom of the platen, and means at the delivery side of the platen, namely, the rear thereof, in position to receive and accumulate the typed work-sheets discharged by the platen.

3. In a front-feed typewriting machine 55 of the front-strike type, the combination with a revoluble platen, of a front sheet-introducer comprising a sheet-supporting floor above the platen, at the front thereof, and a sheet-deflector, in proximity to but spaced from the platen above the writing line thereof, to hold a work-sheet in the machine back in writing position, but far enough forward to diverge the sheet upwardly and forwardly from the floor to 60 form a funnel therewith for the reception of a succeeding work-sheet fed down along the floor to the platen, feed-rolls co-operating with the platen to feed the work-sheets 65 around the platen from front to rear, and to deposit them at the rear of the platen, and a receiving bin on the carriage at the delivery side of the platen to receive the work-sheets 70 from the platen and accumulate them.

JOHN A. WHERRY.
